CLAIM

The ornamental design for a mechanical pencil, as shown and described.

DESCRIPTION

FIG. 1 is a perspective view of a mechanical pencil, showing our new design;

FIG. 2 is a front view of the mechanical pencil;

FIG. 3 is a rear view of the mechanical pencil;

FIG. 4 is a top view of the mechanical pencil;

FIG. 5 is a bottom view of the mechanical pencil;

FIG. 6 is a left side view of the mechanical pencil;

FIG. 7 is a right side view of the mechanical pencil; and,

FIG. 8 is an enlarged bottom view of the mechanical pencil. The parts shown in broken lines are portions of the mechanical pencil that form no part of the claimed design.

1 Claim, 5 Drawing Sheets
